SHOE BOX

Richard B. Brinnon, Wichita, Kans.

Application July 10, 1934, Serial No. 734,532

3 Claims. (Cl. 229—46)

My invention relates to an improvement in boxes, such as shoe boxes and the like. The object of my invention is to provide a shoe box in which the end of the box opens instead of the top so that a series of boxes may be piled one on top of another and the contents of the boxes may be removed and replaced without removing the box from the shelf or the pile of boxes in which it is located. Another object of my invention is to provide a shoe box having a lid or closure element which is attached to the box. A still further object is to provide a box of the kind mentioned and in addition thereto to provide a box having a string attached thereto which may be used to tie the box shut or the string may be used as a pull to open the box while it is on the shelf or in a pile of boxes. These and other objects will be more fully explained as this description progresses.

Now referring to the drawing in which the same reference character designates the same part throughout the several figures: Fig. 1 is a perspective view of my improved box showing the box as it is used on the shelf or in a pile of boxes. Fig. 2 is a perspective view of my improved box showing the end partly opened. Fig. 3 is a perspective view of my improved box showing the box tied up so that it may be carried and the end will not open so as to lose the contents 30 of the box. Fig. 4 is an enlarged detail sectional view through the opening end of the box. Fig. 5 is a perspective view of the box, parts of which are broken away for convenience of illustration.

In the drawing is shown a box 10 having an open end 11 in which is fitted a closure element 12 that is provided with an inwardly extending flange element 13 which extends along the upper edge and both sides of the closure element 12. The lower end of the flange 13 adjacent the hinge 40 14 is cut square as illustrated at 13' so that when the closure element 12 is in the closed position, as shown in Figs. 1, 3 and 4, the square ends 13' strike the bottom of the box and act as a stop so that the upper end of the closure element 12 will not lean into the box and present a bad appearance of the box. At 14 is a strip of paper or tape that is attached, preferably by being glued, to the lower edge of the closure element 12 and the edge 10' of the box 10 and functions 50 as a hinge on which the closure element 12 is swung.

At 15 is a fibrous or paper disk attached to the box 10 by means of an eyelet 16 which provides a hole 17 through both the edge of the box 10 and the disk 15. On the flange 13 is rigidly attached

a round, convex faced, button-like element 18, which, when the closure element 12 is in its closed position, seats itself in the lower edge of the eyelet 16 and functions as a means of retaining the closure element 12 in its closed position 5 as shown in Figs. 1 and 4.

At 19 is a second fiber or paper disk attached to the closure element 12 by an eyelet 20. One end 21 of a string 22 is passed through the hole in which the eyelet 20 is positioned and the eyelet 10 10 functions as a means of holding the end 21 of the string 22. The end 21 of the string 22 is provided with a knot 23 to prevent the end 21 of the string from being pulled from between the eyelet 20 and the side of the hole in which the eyelet 20 and the end 21 of the string 22 is positioned.

When the boxes are in stock, that is they are on the shelves and piled two or three or more boxes high, the string 22 is left to hang inside 20 the box as shown in Fig. 4 and a portion of the string 22 is left as a loop 24 which projects from under the disk 19 and from between the edges of the box 10 and the closure element 12. This loop 24 functions as a pull by which the closure 25 element 12 may be pulled open so the contents of the box may be removed without removing the box from the shelf or pile in which it is positioned.

In packing shoes in boxes it is preferable to have something between each shoe so that the 30 shoes will not rub against each other and become marred or defaced. Therefore I have provided a separator strip 25, the rear end 26 of which is bent and is cemented to the rear end 10a, of the box 10, thereby forming a hinge-like joint 35 at the point 27, thereby leaving the separator 25 free to swing sideways within the box 10. Attention is called to the fact that the rear end of the separator 25 is positioned closer to one side of the box than the other. This is done so that 40 in packing shoes in the box, the heel end of the shoe, which is the widest part of the shoe may be placed in the portion B of the box, which is the widest side of the box, after which the division 25 may be swung over against the toe of the shoe 45 which is the narrow part of the shoe, thereby leaving the divider 25 standing at a diagonal position within the box as illustrated in Figs. 3 and 5. The toe of the next shoe may be entered in the space C, which is the narrow remaining portion of the box and the heel end of the shoe of course would be in the opposite end of the box.

In showing shoes to a customer it is preferable to show the shoe for the right foot, therefore in packing the shoes in my improved box the right 55

shoe may be placed in the compartment C which is the wide compartment at the front end of the box and the clerk will naturally remove the shoe which is easiest to get hold of. Therefore if the 5 shoes are properly packed in the box it will not be necessary when showing the shoes to take the time to inspect the shoe to see whether it is for the right or left foot.

To illustrate the use of the box, we will assume that the box is used in the shoe business and is placed on shelves in the store and in piles of two or three high and each box contains a pair of shoes. Now, the shoes are to be removed from these boxes for the purpose of showing 10 the shoes to customers. The practice now is that the box is necessarily removed from the shelf or pile of boxes in which the box is positioned, the cover removed from the box and placed on the bottom thereof, the shoe removed 15 from the box and then the box is replaced on the shelf or in the pile from which it came and then the shoe clerk may proceed to show his customer the shoe. By using my improved box it is only necessary for the clerk to take hold of 20 the loop 24 and pull the closure element 12 open and remove the shoe or shoes from the box and show it to his customer. When the clerk sells the shoes, he removes the box from the shelf or pile of boxes in which it is positioned, replaces 25 the shoes in the box, closes the closure element 12 and the cord or string 22 is intertwined between and beneath the disks 15 and 19 as illustrated in Fig. 3, which functions as a means of 30 tying the box closed, whereupon the box may be handed to the customer and the time and wrapping paper and string now required to prepare the package to hand to the customer is eliminated.

Such modifications of my invention may be 40 employed as lie within the scope of the appended claims without departing from the spirit and intention of my invention. Now having fully described my invention, what I claim as new and desire to secure by Letters Patent is:

45 1. A box, said box having an open end and a closure element therefor, said closure element being hingedly attached to said box and a flange bounding said closure element, a disk attached to the upper side of said box by an eyelet, a button on said flange, said button being so positioned that it will seat itself in the said eyelet when the closure element is in a closed position 50 and functions to hold the closure element in said

closed position, a second disk, said second disk being attached to said closure element, a string, one end of said string being attached to said closure element so that it may be used as a pull by which the closure element may be pulled open or the string may be intertwined beneath said disks as a means of securing the closure element in a closed position. 5

2. A box, said box having an open end and a closure element therefor, said closure element 10 being hingedly attached to said box, a continuous flange bounding the free sides of said closure element, said flange fitting within said box, said flange being cut square at the ends adjacent the hinge so that the flange will strike the 15 lower side of the box when the closure element is in the closed position and function as a stop to prevent the upper end of the closure element from entering the box too far, a button on said flange, a disk on the outside of said box, said 20 disk being attached to said box by an eyelet which serves the dual purpose of attaching the disk to the box and also forming a seat to receive said button as a means of retaining said closure element in a closed position, a second 25 disk, said second disk being attached to said closure element, a string, said string being attached to the closure element and serving the dual purpose of providing a pull by which the closure element may be pulled open and said 30 string being adapted to be intertwined between and beneath said disks to tie the closure element in a closed position.

3. A box, said box having an open end and a closure element therefor, a separator in said box, 35 said separator being hingedly attached to said box for adjusting purposes; said closure element being hingedly attached to said box and a flange bounding said closure element, a disk attached to the upper side of said box by an eyelet, a button on said flange, said button being so positioned that it will seat itself in the said eyelet 40 when the closure element is in a closed position and functions to hold the closure element in said closed position, a second disk, said second disk being attached to said closure element, a string, one end of said string being attached to said closure element, so that it may be used as a pull by which the closure element may be pulled open or the string may be intertwined beneath 50 said disks as a means of securing the closure element in a closed position.

RICHARD B. BRINNON.
